UNITED STATES PATENT OFFICE.

GEORGE W. STEWART, OF RISING SUN, INDIANA.

SLIDING GATE.

SPECIFICATION forming part of Letters Patent No. 398,861, dated March 5, 1889.

Application filed February 16, 1887. Serial No. 227,833. (No model.

To all whom it may concern:

Be it known that I, GEORGE W. STEWART, a citizen of the United States, residing at Rising Sun, Ohio county, State of Indiana, have 5 invented a new and useful Improvement in Sliding Gates, of which the following is a specification.

This invention has relation to sliding gates, and has for its objects the provision of a gate 10 adapted for use in closing two adjacent fields to permit of the passage of teams, and to provide said gate with a smaller gate at one or both sides for the entrance of foot-passengers, both gates to be operated by the same mechanism, and the smaller gate adapted to be operated first and independent of the larger.

Other objects and advantages of the invention will hereinafter appear, and the novel features thereof will be particularly pointed 20 out in the claims.

Referring to the drawings, Figure 1 is a side elevation of a gate constructed in accordance with my invention, the same being shown in a closed position; and Fig. 2 is an end elevation showing the means for operating the gates.

Like letters of reference indicate like parts in both figures of the drawings.

A A represent the usual uprights or posts, 30 which are oppositely located and connected at their upper ends by a cross-beam, A', one of said posts being provided upon its inner face with rollers A² A³.

B represents the main gate, used for the 35 passage of teams, which gate when in a closed position extends at each side of the post A, and consists of the longitudinal rails B' and vertical risers B², the gate being stiffened by suitable diagonal braces. Upon that side of 40 the gate B next to the rollers A², and secured to the rails B', are longitudinal tracks B³, the upper of said tracks taking under the flange of the roller at the top, and the lower one of the tracks riding upon the lower of said rollers.

At one end of the gate B, and working in the two front and oppositely-arranged risers, there is mounted a small gate, C, the rails of 45 which take into the spaces formed by the rails of the main gate. Oppositely-arranged braces C' secure the ends of the rails of the smaller

gate together and prevent said gate from being displaced, and journaled in the braces of the smaller gate, and between the rails thereof and those of the larger gate, are frictional 55 rollers C².

D represents the usual posts, between which the gates operate, and which may be provided with rollers D', upon which the main gate rides, a pair of them being placed at each side 60 of the posts A.

E represents a gravity-latch adapted to take into a notch, E', formed in the top rail of the main gate at its middle. When this latch is in position in the notch, by devices to be here- 65 inafter described the smaller gate can be independently operated; or when this latch is removed both gates may be drawn back to permit the passage of a team.

F represents a rock-shaft journaled trans- 70 versely in the uprights A, from which extend rigid rock-arms F', depending from the ends of which are operating cords or chains F². In each of the uprights A are pivoted arms G, from which depend cords G', said arms being 75 coupled with the rock-arms F by means of links G². Rigidly attached to the rock-shaft F is a depending arm, H, to the lower end of which is pivoted an arm, H', which is ex- 80 tended forward and pivoted near the front end of the smaller gate. This arm H' is removably pivoted, and may be transferred to the small gate at the opposite end of the main gate, as shown by dotted lines, Fig. 1. From this it is evident that a pull upon the cords 85 F² or G' will draw down upon the rock-arm F', which will oscillate the rock-shaft and force the arm H rearwardly, and this in turn will draw upon the smaller gate, and thus open the same for foot-passengers. The gate 90 will stop when its front risers come in contact with the front risers of the main gate, and it is also evident that if the gravity-latch be lifted from the notch E' the pivoted arms will continue to draw upon the smaller gate, 95 and that when the risers thereof have reached their rearmost position the draft will come upon the main gate, and the two gates will be drawn back for the passage of teams. It now

remains to provide means for removing the 100 latch E from its notch E' at the proper moment. This I preferably accomplish by

mounting an extra rock-arm, E³, on the shaft F and connecting said arm with the latch by a line or chain, E², having just sufficient slack to permit of the smaller gates being operated by the turning of the rock-shaft before the line is drawn taut and acts upon the latch. It is apparent that a continuous pull will withdraw the latch and abut the small gate against the bars B² of the adjacent large gate, 10 and thus the two gates may be opened.

A removable pin, I, is passed through one of the uprights, against which a stop, I', at each end of the main gate is adapted to come, and thus prevent the complete withdrawal of 15 the gate.

It is apparent that the gates may be operated from either side and in either direction, and thus serve the purpose of closing two adjacent fields formed by the intersecting rails 20 J. When the gates are both open, by drawing upon a cord G' or upon one of the cords F², which are designed for the use of foot-passengers, the smaller gate will be pushed forward, and when it reaches the limit of its 25 forward movement it will draw the larger gate thereafter.

C³ represents oppositely-arranged divergent arms adapted for the reception of the advancing end of the smaller gate and to guide the 30 same to its proper position with relation to the posts D. The inner pairs of posts D may be hinged or made removable, so as not to form any obstacle to the entrance of large machines.

35 Having described my invention and its operation, what I claim is—

1. In a sliding gate, the combination of a main gate provided with tracks, uprights having rollers adapted to receive said tracks, a smaller gate mounted and adapted to reciprocate within one end of the main gate, a rock-shaft journaled in the uprights and provided with rock-arms for operating the same, and a jointed arm connected to the rock-shaft and pivoted to the smaller gate, substantially as 40 specified.

2. In a sliding gate, the combination of a main gate provided with tracks, uprights having rollers adapted to receive said tracks, smaller gates mounted at each end of the 45 main gate, a rock-shaft journaled in the uprights and provided with rock-arms for operating the same, and a jointed arm connected to the rock-shaft and pivoted removably to one of the gates and adapted to be pivoted to 50 the other, substantially as specified.

3. The combination, in a sliding gate, of a main gate having a notch and carrying a smaller gate at one of its ends, uprights for supporting the main gate, provided with a 55 gravity-latch adapted to take into said notch and with a rock-shaft having rock-arms one of which is loosely connected with said latch, and a pivoted arm connecting the rock-shaft with the smaller gate, substantially as specified.

In testimony of which invention I hereunto set my hand.

GEORGE W. STEWART.
